UNITED STATES PATENT OFFICE.

JESSE C. WELLES, OF HEMET, CALIFORNIA.

WALNUT DEHYDRATER.

Application filed December 28, 1928. Serial No. 157,536.

This invention relates to an improved apparatus constructed to operate as a drier, the same being especially intended to function as a dehydrater for walnuts and the like.

5 A very ordinary method of drying walnuts consists in the use of an open tray having a foraminous bottom upon which the nuts are adapted to be placed in a manner to allow a natural circulation of air for drying. This method although very slow, is very successful frequently, but only under good weather conditions.

10 Heavy fogs, rain and other inclement weather render the tray type of driers impractical. As a result of this, there are on the market at the present time, various kinds of dehydrating apparatus, especially constructed for drying walnuts. In all of the machines with which I am familiar, heated air at a given temperature, is circulated thru the nut containers. However, these devices embody intricate machines, heaters, costly fans and motors, thus rendering the device substantially prohibitive to a small nut grower.

15 What I propose to do, is to provide a less costly machine such as may be employed to advantage by a small grower, the improved device having substantially all of the advantages of the more expensive ones and being even more successful in that it does away with the heated air and employs the old method of natural circulation of air.

Briefly, the improved apparatus comprises 20 a housing composed of metal and wood, the same being constructed to provide a plurality of individual nut bins, these bins having screen bottoms constructed to cause the nuts to be discharged by gravity and to allow a circulation of air, under pressure, through the bin for effectively drying the nuts.

The particular structural features of the invention will become more readily apparent 25 from the following description and drawings.

In the accompanying drawing forming a part of this application and in which like numerals are employed to designate like parts throughout the same:—

30 Figure 1 is a fragmentary side view showing the complete apparatus.

Fig. 2 is an end view with a portion broken away to disclose the internal structural arrangement.

Fig. 3 is a relatively small perspective view giving the general configuration of the structure.

Figure 4 is a perspective view of one of the details, and

Figure 5 is a perspective view of another one of the details of the invention.

In carrying out the invention, I employ a housing which is generally designated by the reference character 1. In end elevation, this 65 housing is substantially hexagonal. However, this particular shape is not controlling. The end wall in each instance, designated at 2, is provided adjacent its bottom with an opening, the upper half of which is segmented in construction and closed by a screen 3. The lower half of the opening embodies the hingedly mounted screened door 4. On the interior of the housing is a central longitudinal partition 5 from which transverse partitions extend in order to form a plurality of bins 6, of the configuration shown in Fig. 2. Each bin is open at its top, and a hingedly mounted cover or door 7 is provided for closing the bin. The door is downwardly 75 inclined to act as a good water shed.

At the apex of the top of the housing is a weather shield 8. This shield is so constructed as to overlie the hinged ends of the doors and to prevent entrance of water. The bottom of the bin is constructed of screen mesh 9 supported from strips of material and it will be noticed from Fig. 1, that there are two screens in each bin and these screens are shaped to form receivers. The side walls are 80 inclined toward each other and the central bottom wall is inclined downwardly and outwardly and forms a discharge communicating with the side wall of the housing. This opening is closed by a sliding door 11 mounted on guides 12.

The elevation is such as to permit proper disposition of a filling sack 13 which may be suspended from hooks or the like 14, (see Fig. 2). The entire housing is secured to a pair of longitudinally extending runners or rails 15 and it will be noticed that diagonal braces 16 are connected with these runners and side portions of the housing in order to secure rigidity of construction. Of course there are other bars and strips in the general framework which need not be described here.

By directing attention to Fig. 1, it will be seen that a horizontal shaft 17 is mounted

for rotation in appropriate bearings and on the ends of this shaft are fans 18. On the center of the shaft is a belt pulley. Moreover beneath each set of bins is a dirt discharge chute 21. There are two of these chutes which extend from the center of the housing downwardly and outwardly, and communicate with the rectangular opening closed by the aforesaid hinged door 4.

10 The fans are preferably located inwardly of the screen. One purpose of this chute is, as indicated, to discharge dirt collected therein by gravity. Another purpose is to aid in conducting the air current from the 15 fan upwardly and into the bin. I might state in this connection that in the present construction, there are four bins, there being two screen receivers at the bottom of each bin and under each set of bins, is the discharge chute 21. Moreover in order to obtain uniform circulation of air, there is a 20 fan at each end of the device.

In practice, the shaft may be driven in either direction. When operated in one direction, it draws the air in through the 25 screen 3 at the ends and drives it upwardly through the screened bottoms of the bins. I might state however, that the circulation is only permitted when the door of the bin is open. In this way, the air circulation can be regulated. Then too, instead of forcing the air upwardly through the nut, it may be drawn downwardly thru them by reversing the direction of movement of the 30 fan. As before stated, natural air has been employed, and it is found that this dries the nuts perfectly and maintains them in a better condition than when acted upon by heated air.

40 It is thought that by considering the detailed description in connection with the accompanying drawings, a clear understanding of the construction and features will be obtained. Therefore a more lengthy description is thought unnecessary.

While the preferred embodiment of the invention has been shown and described, it is to be understood that minor changes coming within the field of invention claimed may be resorted to if desired.

Having thus described my invention, what I claim as new is:—

1. A dehydrater of the class described comprising a housing provided with a bin open at its top, a closure for said top, a discharge opening in one side of said bin, a closure for said opening, and a screened bottom in said bin and embodying downwardly converging side walls and a downwardly and outwardly inclined bottom wall, 55 leading to said discharge opening.

2. In a dehydrater of the class described, a housing having longitudinal and transverse partitions on its interior dividing it into a plurality of compartments forming 60 nut receiving bins, a screened bottom for said bins, the bins being open at their tops, individual closures for said open tops, discharge chutes located beneath said bins, a shaft journaled for rotation upon said housing, and fans on the opposite ends of the 65 shaft for circulating air simultaneously through the bins when uncovered.

3. In a dehydrater of the class described, a housing embodying a nut receiving bin, 70 which is open at its top, a hingedly mounted downwardly inclined cover for said open top, a screened receiver forming the bottom of said bin, said receiver being constructed to cause the nuts to discharge therefrom by gravity, an opening cooperable with the discharge end of the receiver, a closure for said opening, a downwardly and outwardly inclined chute located beneath said receiver, a shaft extending rotatably through said chute 75 and a fan on the outer end of the shaft adjacent the discharge end of said chute.

In testimony whereof I affix my signature.

JESSE C. WELLES.
